[57] ABSTRACT

A new and distinct cultivar of African violet named Little Hopi Girl characterized by its mid-size growth habit (13-15 cm in diameter); pink, star-shaped flowers; strong stems which curve toward the center to form a compact bouquet above the leaves; profuse flowering; bright green, spear- to heart-shaped leaves; flowering 10-11 weeks after planting of unrooted shoot, and by its long lasting and non-dropping flowers.

Primary Examiner—James R. Feyrer

1 Drawing Sheet

1

The present invention comprises a new and distinct cultivar of African violet plant, botanically known as *Saintpaulia ionantha*, and hereinafter referred to by the cultivar name Little Hopi Girl.

The new cultivar was referred to during the breeding and selection process by the designation 46 II and is a product of a planned breeding program. The new cultivar was originated from a cross made by me in the controlled breeding program in Haffen, Federal Republic of Germany. The female, or seed parent was a cultivar designated 69 red single. The male, or pollen parent was a cultivar designated 461.

Little Hopi Girl was discovered and selected by me as a flowering plant within the progeny of the stated cross in a controlled environment in Haffen, West Germany. Asexual reproduction of the new cultivar by leaf cuttings, as performed by me at Haffen, West Germany, has demonstrated that the combination of characteristics as herein disclosed for the new cultivar are firmly fixed and retained through successive generations of asexual reproduction.

Little Hopi Girl has not been observed under all possible environmental conditions. The phenotype may vary significantly with variations in environment such as temperature, light intensity and day length. The following observations, measurements and values describe the new cultivar as grown in a 5.5 cm pot in Haffen, West Germany and Nashville, Tenn. under greenhouse conditions which closely approximate those generally used in commercial practice.

The following traits have been repeatedly observed and are determined to be basic characteristics of Little Hopi Girl, which in combination distinguish this African violet as a new and distinct cultivar:

- (1) A single crown will not grow larger than 13-15 cm.
- (2) Light pink, star-shaped flowers.
- (3) Strong wirelike and upright flower stems curving toward the center.
- (4) First flush of flowers form a tight bouquet above the leaves.
- (5) Profuse flowering.
- (6) Each plant carries 7-9 and more upright flower stems each of which carries 3-5 and more flowers.
- (7) Long lasting, non-dropping flowers.
- (8) Plant saleable 10 to 11 weeks after planting of unrooted shoot.
- (9) Seed capsules push slightly through.

2

(10) Bright green, spear- to heart-shaped leaves are 3-4 cm in size.

(11) After maturity the flowers dry off, and remain on the peduncle.

The accompanying color photographic drawings shows a typical specimen plant of the new cultivar grown in a 5.5 cm pot. The colors appearing in the photograph are as true as possible with color illustrations of this type.

In the following description, color references are made to The Royal Horticultural Society Colour Chart (R.H.S.), except where general colors of ordinary significance are referred to. Color values were taken under natural sunlight conditions at approximately 12 a.m. in Nashville, Tenn.

Botanical classification: *Saintpaulia ionantha*, Ramat., c.v. Little Hopi Girl.

Parentage:

Male parent.—461.

Female parent.—69 red single.

Propagation: The new cultivar holds its distinguishing characteristics through successive propagations by leaf cuttings.

Plant: From 7 cm to 9 cm tall when grown in pots, and approximately 13-15 cm in diameter when fully grown.

Leaves:

General form.—Spear- to heart-shaped.

Diameter.—30-35 mm wide and 30-40 mm long.

Texture.—Leatherlike.

Aspect.—Hairy, slightly shiny.

Veins.—Uppercide: visible; underside: well pronounced, light green to pinkish green, shiny.

Color (upperside).—Yellow-Green Group 147 between A and B.

Color (underside).—Greyed-Purple Group 186 B to C. Petiole: Strong, green with purplish red touch, hairy.

Flowers:

Buds.—Size: 7-8 mm just before opening. Shape: Bell-shaped. Color: Pinkish green.

Sepals.—Five (5). Color: Green with brownish touch.

Calyx.—Shape: Funnel-shaped. Aspect: Spear-shaped, hairy.

Plant 7,695

3

Peduncle.—Character: Strong upright, hairy.
Color: Green with purplish red touch.

Individual flowers:

Size.—30 mm.

Shape.—Star-shaped.

Color (upperside).—Violet Group 82 C to D, center

Purple Group 80 A. Under cooler temperatures and more intensive lighting, the pink tends to intensify.

10

Color (underside).—Purple Group 75 C to D.

Borne.—Each flower stem carries 3-5 and more flowers on strong, upright peduncles that are free standing above the leaves, thereby forming a compact bouquet.

15

Flowering habit.—Flowers 10-11 weeks after planting an unrooted plantlet.

Reproductive organs:

Stamens.—Five (5). Anthers: 5 composed of 10 anther cells, seed capsule pushes slightly through.

Filaments.—Greenish white, 3-4 mm long.

Styles.—5-6 mm long, pink, base of ovary light green and hairy.

25

Roots: Normally developed, white when young, turning slightly brownish when older.

4

Disease resistance: Up to date, Little Hopi Girl has shown very good resistance to all major violet diseases.

General observations: Little Hopi Girl is a mid-size violet, a size between a regular violet (grown in a 10 cm pot), and a supermininature (grown in a 4 cm pot). Little Hopi Girl is designed to be grown in a 5.5 to 6 cm pot and will not grow larger than 13-15 cm. Each of the 7-9 and more strong flower stem carries 3-5 and more light pink, star-shaped flowers which contrast nicely with the multiple bright yellow anthers. A nice bouquet of flowers free standing above the bright green, spear- to heart-shaped leaves develops approximately 10-11 weeks after planting an unrooted plantlet. The flowers have a darker center and are long-lasting and non-dropping.

I claim:

1. A new and distinct cultivar of African violet named Little Hopi Girl, as described and illustrated, and particularly characterized by its mid-size growth habit (13-15 cm in diameter); pink, star-shaped flowers; strong stems which curve toward the center to form a compact bouquet above the leaves; profuse flowering; bright green, spear- to heart-shaped leaves; flowering 10-11 weeks after planting of unrooted shoot, and by its long lasting and non-dropping flowers.
